CLAIM

We claim the ornamental design for a fan cover for wireless communication repeater, as shown and described.

DESCRIPTION

FIG. 1 is a front perspective view of a fan cover for wireless communication repeater showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged cross-sectional view taken through line 9-9 of FIG. 2.

The dash-dash broken lines in the figures depict environmental subject matter and form no part of the claimed design. The dot-dash broken lines in the figures illustrate a boundary of the claimed design and form no part of the claimed design.
